UNITED STATES PATENT OFFICE.

JOSEPH VOGT, OF NEW YORK, N. Y., ASSIGNOR TO PAPERHANGERS
MACHINE COMPANY, A CORPORATION OF MAINE.

MACHINE FOR TRIMMING AND PASTING WALL-PAPER.

No. 884,087.

Specification of Letters Patent.

Patented Oct. 23, 1906.

Application filed October 17, 1905. Serial No. 283,128.

To all whom it may concern:

Be it known that I, JOSEPH VOGT, a citizen of the United States, residing in New York, in the borough of Manhattan and State of New York, have invented certain new and useful Improvements in Machines for Trimming and Pasting Wall-Paper, of which the following is a specification.

This invention relates to certain improvements in a wall-paper trimming and pasting machine, for which Letters Patent were granted to me, No. 742,808, dated October 27, 1903, the improvements being designed with the view of improving the working of the machine, improving the arrangement of the paper guiding and trimming mechanisms, rendering the paste-receptacle removable, and permitting the folding up of the machine after use within a comparatively small compass, so as to permit the convenient carrying of the same from the place of use; and for this purpose the invention consists of a wall-paper trimming and pasting machine comprising a metallic supporting-frame provided with foldable legs and a hinged folding cover forming a table when in open position, a sliding paste-receptacle in the supporting-frame, said receptacle being provided with a paste-transmitting roller and scraper or so-called "doctor," a detachable paper-roll support applied to the outside of the frame, rollers for feeding the paper to the paste-transmitting roller, fingers for guiding off the trimming cut from the wall-paper, and rotary adjustable knives for trimming the wall-paper to the proper width.

The invention consists, further, of certain improvements in the indicator for showing the length of the wall-paper fed through the machine, and, lastly, of additional details of construction and combinations of parts, which will be fully described hereinafter and finally pointed out in the claims.

In the accompanying drawings, Figure 1 represents a side elevation of my improved wall-paper trimming and pasting machine, showing the same in position for use. Fig. 2 is a front elevation of Fig. 1. Fig. 3 is a side elevation of the opposite side of the machine. Fig. 4 is a plan view of Fig. 1. Fig. 5 is a vertical transverse section. Fig. 6 is a sectional plan view of the roll-support shown in Fig. 5. Fig. 7 is a detail plan view, in hori-

zontal section, of the trimming mechanism. Fig. 8 is a detail side view of the indicator mechanism. Figs. 9 and 10 are an end elevation and a vertical section on line 10-10, Fig. 8, of the indicator mechanism. Fig. 11 is a detail section of the paste-transmitting roller. Fig. 12 is an end elevation, partly in section, of the same; and Figs. 13, 14, and 15 are details of the trimming mechanism.

Similar letters of reference indicate corresponding parts in the different figures of the drawings.

Referring to the drawings, A represents an oblong box or frame which is preferably made of sheet metal, the length of which is made large enough to permit the pasting of the sizes of wall-paper in the market. The metallic box or frame A is supported on folding legs b, which are provided with braces b', the legs being pivoted to bottom flanges of the box, so as to be folded upon the same when the machine is not required for use. The metallic box A is made open at the rear end, so as to permit the removal of a paste-receptacle P, which is approximately of the size of the box or frame A, so as to be supported within the same and readily removed therefrom for being refilled with paste when the same is exhausted. The metallic box or frame A is closed by means of a cover C, which is formed of two parts, an angular portion C', the longer part of which is guided in ways in the bottom of the metallic frame A, while the shorter part extends along the front of the same, and a hinged section C², which extends over the top part of the frame and is attached thereto, so as to inclose the parts when the machine is not required for use. The longer part of the rectangular section of the cover is guided by means of pins in the ways in the bottom of the metallic frame A and is permitted to swing in downward direction in keepers k, so as to assume the position shown in Fig. 1, in which the cover forms at the same time a table for the paper after the same leaves the machine. The roll of wall-paper X is supported in a bracket-support D, as shown in Figs. 5 and 6, that is attached to the rear part of the frame A, the supporting-brackets being made extensible, so as to fit any size of roll. The main bracket-support d^x is provided with headed studs d, which are inserted in slots in

the rear wall of the metallic frame A and clamped in position by a suitable clamping-screw d' , while the adjustable bracket d^2 is guided on the main bracket and adjusted thereon by a clamping-screw d^3 , as shown in Fig. 6. By loosening the clamping-screws d', d^3 with the adjustment of the bracket d^2 the bracket-support can be removed from the frame and stored away in the upper part 10 of the metallic frame, so as to be readily carried with the machine when the same is not required for use. When the machine is to be used, the main bracket is inserted by its headed studs into the slots of the metallic 15 frame A and clamped in position, after which the adjustable bracket d^2 is set to the proper size of roll and then clamped in position after the pins at the ends of the brackets are inserted into the opposite ends of the wall- 20 paper roll.

In the paste-receptacle is arranged a paste-transmitting roller E, which is supported in suitable bearings in the side wall of said receptacle, one bearing for the shaft of the roller 25 being socket-shaped, while the opposite head of the roller is provided with a coupling device, by which it is connected with a short shaft e, that turns in bearings of the opposite side wall of the paste-receptacle P, said coupling consisting of a key K, that is passed 30 through a U-shaped bearing w at the head of the roller and a transverse roller in the short shaft, the key being locked in position after insertion between lugs l, arranged on the head of the roller, as shown clearly in Fig. 12. By withdrawing the key, the paste-transmitting 35 roller can be turned until its U-shaped bearing is, with its open end, below the short shaft, so that the roller can be lifted out of 40 the receiver for cleaning and repairing. It is replaced in the receiver in the reverse order and then locked again in position by the coupling-pin, which is firmly held in position between its two supporting-lugs, as 45 shown in Fig. 12. A doctor or scraper E' is supported in bearings of the side walls of the paste-receptacle P, the end being pressed on the paste-transmitting roller, so as to remove the surplus paste before the same comes in 50 contact with the wall-paper.

The upper part A' of the metallic frame is made separate from the lower part and hinged at one end, so as to be thrown open 55 sidewise. In said upper part of the metallic frame are supported the bearings for one feed-roller N, which moves in contact with a second feed-roller N, the shaft of which is supported in bearings in the lower or main part of the frame, and the bearings for a presser- 60 roller O, which moves in contact with the paste-transmitting roller E in the receptacle P. Between the upper feed-roller and the presser-roller is arranged an indicator I, which is operated at each rotation of the up- 65 per feed-roller, so as to indicate the number

of feet of wall-paper that have passed through the machine and indicate thereby when the proper length of paper is trimmed and pasted, so that the paper-hanger can take it up from the table and hang it on the wall. At the 70 upper rear end of the main portion of the metallic frame A, adjacent to the lower feed-roller, is arranged a transverse bar F, over which the wall-paper is conducted from the roll to the feed-rollers N and paste-transmitting roller. The rotary feed-rollers bring the paper over the transverse bar and conduct it over an inclined plate t, that is arranged 75 between the lower feed-roller and the presser-roller to the paste-transmitting roller, which transmits paste to the under side of the paper, which is then conducted over suitable fingers f⁴, arranged at the upper front part of the main portion outside of the metallic frame and laid up in folds on the supporting- 80 table, as shown in Fig. 1.

The upper feed-roller N carries at one end a small antifriction-roller n^x, as indicated in dotted lines in Fig. 8, which roller in being moved in a circular path periodically abuts 85 against the beveled end of a slide-bar i, whereby said bar is pushed forwardly, after which it is returned to normal position by a spring n¹⁰, engaging the opposite end thereof. Said bar i carries a spring-actuated pawl g¹, 90 which engages and actuates in one direction a ratchet-wheel g², said ratchet-wheel being prevented from movement in the opposite direction by a pivoted and spring-actuated check-pawl g', as shown. To the shaft of the 95 ratchet-wheel is applied an index-hand, which moves over a dial on the face of the indicator, so as to indicate thereby the number of feet of wall-paper that have passed through the machine. The antifriction-roller n^x in abutting 100 against and pushing inwardly the slide-bar i during each rotation of the upper feed-roller effects the forward movement of the ratchet-wheel to the extent of one tooth, and the pointer indicates this movement on 105 the dial, which is so graduated as to properly measure the paper. When the required length is obtained, the paper is cut off, removed from the table, and hung up. The 110 pointer is set at zero by releasing the push and check pawls from the teeth of the ratchet-wheel by a sliding and spring-actuated pusher p, which extends above the indicator and which can be readily operated by the thumb, so as to release the pawls. This permits the return of the index-point to zero for 115 pasting the next quantity of paper. A coil-spring is arranged in front of the ratchet-wheel at its inner end, while its other end is attached to the casing of the indicator, as 120 shown in Fig. 8, said spring producing the automatic return of the index-hand to zero as soon as the pawls are released by the pusher-bar.

Above the transverse bar F are supported 130

on the upper hinged portion A of the metallic frame on a transverse supporting-rod two or more disk-shaped cutters h, which are capable of adjustment in a lateral direction on 5 said rod by means of set-screws h', passing through their hubs. Each disk works in connection with a stationary cutter h², which is attached by a set-screw h³ to holes of the transverse bar, the transverse bar receiving 10 motion toward the cutters by means of a helical spring x, that is interposed between its end and the side wall of the casing of the indicator, so that a tight shearing contact is produced, and thereby the proper trimming of 15 the wall-paper obtained. The cutter and stationary cutters are arranged exactly to the width of the wall-paper, so as to trim the edges of the same. The paper is conducted over the fingers f⁴, that are supported on the 20 front part of the lower portion of the metallic frame, while the trimmed-off edges are conducted over larger laterally-adjusted fingers f⁶, that are arranged at each end of the main portion of the metallic frame, as shown in 25 Fig. 4.

Rotary motion is imparted to the feed-rollers, edge-trimming knives, paste-transmitting and presser-rollers by a train of gears arranged at one end wall of the machine and driven by a crank R, applied to the 30 largest gear-wheel, as shown in Figs. 1 and 2. The side walls of the lower portion of the metallic frame are provided with recesses r⁸ to permit the shaft of the paste-transmitting 35 roller to be moved in proper place with the paste-receptacle. On the same side as the gear-wheels is arranged a pivoted locking-link l¹⁰, by which the upper hinged portion A' of the metallic frame can be locked to the 40 lower main portion of the same.

The transverse bar which carries the stationary cutters has at one end a cushion-spring, guided in a socket at one end of the side wall of the metallic frame, while the opposite end is provided with two parallel pins q q'. The pin q is provided with a side recess and interlocks by means of said recess with a recessed cushioned slide-bolt b¹², which is disposed at right angles to said pin and supports 45 said bar in position. This locking engagement may be released by pushing in the slide-bolt b¹², so that it is disengaged from said pin, as shown in Fig. 13. The other pin q' is acted upon by a bar M with a beveled edge, so as to push the transverse bar over against the tension of its spring for producing the adjustment of the stationary cutters, after which the pin and transverse bar are released again for pressing the edge of the 55 stationary cutters against the edge of the circular cutters for producing the trimming of the wall-paper. When the wall-paper has to be cut along the center line, a third rotary cutter is arranged, as shown in Fig. 4. The 60 intermediate cutter can also be used in con-

nection with one of the other knives for cutting off the edges of narrower papers, borders, and the like.

My improved wall-paper trimming and pasting machine is operated as follows: The 70 roll of paper is applied to the supporting-brackets at the outside of the machine and the paper then passed over the stationary cutter-bar and feed-rollers and between the paste-transmitting and presser-rollers, over 75 the fingers, onto the table on the outside of the machine. By passing the paper through the paste-transmitting roller and presser-roller the paste is applied to the under side of the paper. By simultaneous rotation of the rotary cutters in connection with the stationary cutters the edges of the paper are trimmed. The pasted wall-paper is collected in superposed folds in such a manner that the pasted 80 portions come in contact only with each other. 85 When the required length as required by the height of the room is obtained, the paper is cut off and pasted on the wall.

The improved wall-paper trimming and pasting machine can be readily operated, 90 takes up but little room, can be carried readily from the shop to any house to be papered, supplies the wall-paper in uniformly trimmed and pasted condition, so as to be quickly hung to the wall by the paper-hanger. After 95 the work is done the table is returned in position and used as a cover for the machine, while the supporting-legs are folded up to the bottom of the supporting-frame and the roll-supporting brackets removed and stored inside of the machine. In this manner all the parts are properly housed and the machine conveniently carried without requiring extra attendants. By proper adjustment of the edge-trimming knives and the feeding and 100 paste-transmitting rollers the pasted wall-paper is applied in much less time than heretofore, so that the work of the paper-hanger is greatly facilitated and expedited.

Having thus described my invention, I 110 claim as new and desire to secure by Letters Patent—

1. In a machine for trimming and pasting wall-paper, the combination of a supporting-frame embodying superposed sections, a slideable paste-receptacle supported in the lower section, a paste-transmitting roller mounted in said receptacle, a feed-roller journaled in said lower section, a presser-roller journaled in the upper section of said frame and co-operating with said paste-transmitting roller, and a feed-roller journaled in said upper section and co-operating with said first-named feed-roller.

2. In a machine for trimming and pasting 125 wall paper, the combination, with the supporting-frame, of a slideable paste-receptacle in the same, feed-rollers at the upper part of the supporting-frame, adjustable rotary trimming-knives, stationary cutters working in 130

conjunction with said rotary knives for trimming the edges of the wall-paper, a roller for transmitting paste to the under side of the wall-paper, a roll-supporting bracket attached to one side of the supporting-frame, guide-fingers for conducting the pasted and trimmed wall-paper over the opposite side of the supporting-frame, and fingers for conducting the trimmed-off edges to an outside receptacle.

3. In a wall-paper trimming and pasting machine, the combination with the supporting-frame, the paste-receptacle mounted thereon, the paste-transmitting roller, and the presser-roller coöperating therewith, of means for trimming the edges of the wall-paper, guide-fingers on said supporting-frame for guiding the pasted and trimmed wall-paper, and laterally-adjustable fingers mounted on said frame for guiding the trimmed edge portions of the wall-paper.

4. In a machine for trimming and pasting wall-paper, the combination, with the supporting-frame, of feed-rollers at the upper part of the same, a paste-receptacle, a paste-transmitting roller in said paste-receptacle, a presser-roller above said paste-transmitting roller, an indicator located adjacent to the

feed-rollers, said indicator consisting of a graduated dial, a pointer moving over said dial, a pawl-and-ratchet mechanism for operating the pointer, and means for operating said pawl-and-ratchet mechanism from one of the feed-rollers so as to indicate the length of paper passed through the machine.

5. In a machine for trimming and pasting wall-paper, the combination, with the supporting-frame and wall-paper feeding and pasting devices, of a cover consisting of two sections, an angular section guided in ways at the bottom of the supporting-frame provided with pivot-pins at its end, and a hinged section applied to the opposite end of the angular section, and supporting-hooks at the lower part of the supporting-frame for permitting the forward motion and tilting of the cover so as to form a table for the pasted wall-paper or the return of the same so as to inclose the parts of the machine.

In testimony that I claim the foregoing as my invention I have signed my name in presence of two subscribing witnesses.

JOSEPH VOGT.
